REFRIGERATOR CABINET FOR A KEG OF BEVERAGE

Kiyoshi Tobe, Tokyo, Japan, assignor to Nippon Electric
Industry Company Limited, Tokyo, Japan

Filed Dec. 14, 1966, Ser. No. 5,034

Term of patent 14 years

(Cl. D67—3)

FIG.1

FIG.7

FIG.3

FIG.2

FIG.4

FIG.8

FIG.6

FIG.5

FIG.9

FIG.10

FIG.11

FIG. 1 is a front elevational view of a refrigerator cabinet for a keg of beverage showing my new design;

FIG. 2 is a bottom plan view thereof;

FIG. 3 is a rear elevational view thereof;

FIG. 4 is an elevational view taken from one side thereof;

FIG. 5 is a top plan view thereof;

FIG. 6 is an elevational view taken from the side opposite that shown in FIG. 4;

FIG. 7 is a front elevational view of a modified form of the refrigerator cabinet for a keg of beverage shown in FIG. 1;

FIG. 8 is an elevational view taken from one side of FIG. 7;

FIG. 9 is an elevational view taken from the side opposite that shown in FIG. 8;

FIG. 10 is a front elevational view of FIG. 7, with the door removed; and

FIG. 11 is a perspective view of the refrigerator cabi-

net, with the door removed and the top in a raised position.

The broken line representation of a keg in FIG. 11 is for purposes of illustration only.

I claim:

The ornamental design for a refrigerator cabinet for a keg of beverage, as shown and described.
